UNITED STATES PATENT OFFICE.

LEON T. MART, OF KANSAS CITY, MISSOURI.

AIR PREHEATER FOR FURNACES.

Application filed May 23, 1925. Serial No. 32,522.

My invention relates to air pre-heaters, for utilizing the sensible heat in flue gases that have felt a furnace to preheat the air supplied to the furnace for combustion.

5 While applicable to many different types of furnaces I regard the widest application of my invention to be in preheating the air supply of distillation furnaces, and for this reason have illustrated my invention in connection with this type of furnace.

My invention relates more particularly to the supporting and sealing structure at top and bottom of air tubes across a hot flue.

A purpose of my invention is to draw the 15 air supply for a furnace through metal tubes (preferably substantially vertical tubes) that have major portions within a hot flue to a chimney and to provide quick, simple and cheap means for sealing and sealing the pipes.

20 A further purpose is to rest the pipes in sealing engagement with a closure plate at their lower ends and to seal about the pipe at the upper ends by heat insulation.

Further purposes will appear in the specification and in the claims.

I prefer to illustrate my invention by one general form only with a slight modification among the various forms and modifications which may appear, selecting a form which is 30 simple, practical and inexpensive and which at the same time well illustrates the principles of my invention.

Figure 1 is a longitudinal section through a furnace and chimney embodying my invention.

35 Figure 2 is a section of Figure 1, taken upon the line 2—2.

Figure 3 is an enlarged fragmentary section of Figure 2, taken upon the line 3—3.

40 Figure 4 is a section of Figure 3 taken upon the line 4—4.

Figure 5 is an enlarged fragmentary sectional detail illustrating my invention.

45 Figure 6 is a section corresponding to Figure 5 but showing a modification.

Like numerals refer to like parts in all figures.

Referring to the drawings and describing in illustration and not in limitation:—

50 The boiler or still 10 is shown conventionally and may be any one of many different types. It is shown supported by stirrups 11 riveted to the shell and as resting upon opposite walls 12 and 13 of a furnace 14.

The boiler is charged through a supply 55 pipe 15, and the distillation products leave the top of the boiler through a pipe 16. Man-hole 17 is shown at one end to permit ventilation and entry when the boiler is opened up for cleaning.

60 The top and ends of the boiler are shown covered with insulation 18.

The firebox beneath the furnace has a fuel supply (here presumed to be oil) at 19, suitable air inlet 20 and hot flue 21 to chimney 22.

65 I utilize the hot flue 21 to preheat the air supply. For this purpose I roof and floor a portion of the flue with one or more pairs of transverse metal plates 23, 24, respectively (preferably of cast iron), supporting the air-preheating tubes 25 on and in these plates.

70 Each upper plate 23 is bored at 26 to loosely pass the air tubes down from the top and the corresponding lower plate is bored and counterbored at 27 and 28 in registry with the holes at 26 to receive and seat the lower ends of the tubes.

75 The form of seats used at the lower ends of the tubes may comprise various forms of which I show a bore and counterbore fitting 80 the straight end of a tube, as shown in Figures 4 and 5 and in Figure 6 a tapered hole fitting the correspondingly tapered lower end of the tube.

85 In the form shown in Figure 5, the tubes are straight lengths of pipe, uniform throughout their length and without any machining at either end, further than to remove any burr incident to cutting them to length.

90 The bore 27 and counterbore 28 in the lower plate to provide a sealing seat for the lower end of the tube, are respectively of the inside and outside diameters of the tube, the end of the tube resting upon the annular shoulder 29 formed by the counterbore.

95 Obviously a somewhat more perfect fit and seal may be obtained by machining the lower end of the tube to fit a definite perforation in the plate. This is illustrated in Figure 6 where the lower end of the tube has been machined to make taper fit at 30 with a tapered hole 31 through the lower plate.

100 Where machining is to be resorted to, the taper fit seat of Figure 6 offers some advantages over the fit shown in Figure 5; however the seat obtained by the structure in Figure 5 may be sufficient and its cheapness and ease of replacement are much in its favor.

The upper ends 32 of the tubes 25 extend a distance above the plate 23 and a bed of insulating material 33, preferably fireclay, is placed on top of the plate around the open 5 ends of the tubes. This bed of insulation serves the double purpose of affording an easy and effective seal around the ends of the tubes where they pass through the upper plate and of heat insulating the top of the flue from the 10 room.

The duct 34 carrying the preheated air from the lower ends of the tubes to the air inlet 20 is preferably run under the furnace so as to be out of the way.

15 The upper ends of the tubes 25 open into the room, and in operation the air supply for the furnace is drawn from the furnace room through the hot tubes and the duct 20 to the furnace. The tubes are preferably placed in 20 staggered rows across the flue, as seen in Figure 3, so that the hot products of combustion have to travel tortuously to pass them, and none of the tubes are in any wise shielded from these hot gases by any of the other tubes.

25 A notable feature of my invention is the extreme ease with which replacements may be made. The tubes gradually burn out and when they do, replacement is merely a matter of pulling out the faulty tubes and putting in 30 new ones, using a little fireclay to freshly seal them around the top.

In view of my invention and disclosure, variations and modifications to meet individual whim or particular need will doubtless 35 become evident to others skilled in the art and I therefore claim all such in so far as they may fall within the reasonable spirit and scope of my invention.

Having thus described my invention, what

I claim as new and desire to secure by Letters Patent is:—

1. In a preheater for heating inlet air by flue gases, a flue for heated gases, having top and bottom plates apertured to communicate respectively with the atmosphere and with a 45 passage for preheated air supply, the apertures in the bottom plate being tapered in combination with tubes passing through one set of apertures, crossing the flue and pressing longitudinally against the tapered part of the 50 wall about the other set of apertures, pressing thereagainst by reason of weight alone and sealing therewith transversely to the axes of the tubes.

2. In a preheater for heating inlet air by 55 flue gases, a flue for heated gases having opposite plates apertured respectively in communication with the atmosphere and with a preheated air passage, the former aperturing being larger than the latter, and both staggered, in combination with tubes passing through the larger apertures, having tapered lower ends and fitting longitudinally against the wall having the smaller apertures, in line with said apertures, so that the tightness of 60 fit laterally increases with the pressure.

3. In a preheater for heating inlet air by flue gases, a flue for hot gas, upper and lower walls of which are apertured and free from 65 threads, the apertures in the upper wall being the larger, in combination with tubes passing through the apertures in the upper wall and extending above its apertures and a covering of heat insulation sealing material between the tube extensions and the apertures in the 70 upper wall.

LEON T. MART
